(57) **CLAIM**

We claim the ornamental design for a magazine mount, as shown and described.

DESCRIPTION

FIG. 1 is a top perspective view of a second embodiment of a magazine mount, showing my new design;

FIG. 2 is a right side view thereof;

FIG. 3 is a left side view thereof;

FIG. 4 is a top view thereof; being a top view of a magazine mount oriented as shown in FIG. 2;

FIG. 5 is a bottom view thereof; being a bottom view of a magazine mount oriented as shown in FIG. 2; and,

FIG. 6 is a front view thereof, the back view being the same. The broken lines denoting selected segments of the various embodiments are for illustrative purposes only for the particular embodiment shown and form no part of the claimed design.
